UNITED STATES PATENT OFFICE.

JOHN C. MCPHAIL, OF SOUTH WEYMOUTH, MASSACHUSETTS, ASSIGNOR TO FRANK H. THAYER, OF BOSTON, MASSACHUSETTS.

AUTOMATIC STOP AND BRAKE MECHANISM FOR SOUND-REPRODUCING MACHINES.

Application filed June 17, 1924. Serial No. 720,527.

This invention relates to automatic stop and brake mechanism for sound reproducing apparatus of the type employing a rotating turn-table on which the record disc is mounted, with a sound box mounted on a tone arm and equipped with a stylus for engaging the grooves of the record. In certain aspects the invention has to do particularly with an embodiment of such apparatus employing an electric motor for operating the turn-table, and a principal object of the invention is to provide effective and reliable means for automatically as the playing of a record is finished, first disconnecting the source of electric energy, and then applying a brake to the turn-table to stop the machine. A further object is to provide means adapted to be set by a preliminary movement of the tone arm for controlling the automatic stop and brake device, so that it will become operative at the instant the playing of the record is finished. A still further object is to provide improved means whereby the parts are semi-automatically reset in readiness for operation by a single movement of an operating lever or hand piece. The foregoing and other objects and advantages of the invention will more fully appear from the following detailed description taken in connection with the accompanying drawings, and the distinctive features of novelty will be pointed out in the appended claims.

Referring to the drawings:

Fig. 1 is a plan view of a sound reproducing apparatus equipped with the invention, portions being broken away;

Fig. 1^a is a fragmentary view partly in elevation and partly in vertical section, showing a portion of the tone arm and the co-operative relation thereof with the stop mechanism.

Fig. 2 is a partial plan view on a relatively enlarged scale, showing the essential operating elements, the turn-table being removed and a portion of an enclosing cover being broken away;

Fig. 3 is a fragmentary vertical section on line 3—3 of Fig. 2;

Fig. 4 is a partial plan view similar to Figure 2, but showing the parts with the switch thrown out and the brake about to be applied;

Fig. 5 is a partial plan view similar to

Figure 4, but showing the parts with the brake applied;

Fig. 6 is a view of the apparatus partly in elevation and partly in vertical section; and

Fig. 7 is a fragmentary section on line 7—7 of Figure 2.

1 indicates the turn-table of the machine which is mounted as usual upon an upright arbor or rotating post 2, this arbor being journalled in a depending portion 3 of a support structure 4. 5 indicates an electric motor secured in depending relation to the support structure and having driving connections by means of a pinion and gear 6, 7 to operate the turn-table. 8 indicates an electric switch which controls the current supply to the motor 5, this switch having a movable element 8^a, which when pulled outward disconnects the current from the motor while when it is pushed inward the motor is energized. 9 indicates a brake adapted to engage the usual depending peripheral flange 1^a of the turn-table 1. In accordance with my invention means is provided whereby as the playing of a record is finished the switch element 8^a is first pulled out to de-energize the motor and immediately thereafter the brake 9 is applied to the turn-table. The switch member 8^a is born by a depending projection 10 from a plate arm 11, which is pivoted at its inner end at 12 to the fixed support structure. This arm 11 bears a stepped pivot pin 13, to an outer portion of which is pivoted an arm 14 which extends outward through an arcuate slot 15 of a cover plate 16 and bears at its outer end a knob or hand piece 17 for the manual resetting and control of the mechanism, the outer extremity of this arm resting upon, and co-operative with, a segment plate 18 secured to the cover 16. Also pivotally secured to the stud 13 and in frictional engagement with the handle arm 14, is a plate 19 which has an outer portion 19^a relatively enlarged to provide a bearing area upon the cover 16 on which it slides. This outer portion of the arm 19 is equipped with an upward projection 20 which is adapted to engage a shoulder 21 formed on a bent plate arm 22, which is fitted to turn on a pivot 23 borne by the fixed support. The arm 19 is engaged by a tension coil spring 24 which is anchored at 25 to the fixed support, this

100
105

spring tending to swing the arm 19 in a direction to pull out the switch plug 8^a when the shoulder 21 is tripped to release the projection 20. The plate arm 22 may be moved to thus release the shoulder 21 from the projection 20 manually by means of a projection 26 borne by the handle arm 14 engaging a projection 27 at the extremity of the plate arm 22, and the plate arm 22 is also adapted to be tripped automatically by the movement of the tone arm as the playing of a record is completed. For this purpose a plate member 28 is mounted on the pivot stud 23 superposed on the plate 22 and in frictional engagement therewith, such frictional engagement being increased to a substantial degree by a spring washer 29, which is fitted on the outer portion of the stud 23 under a head thereof and thus adapted to press the plate 28 quite strongly against the plate arm 22. The plate arm 22 is engaged by a tension spring 30, which is also anchored at 25, this spring tending constantly to draw the plate arm 22 inward in position for the shoulder 21 to engage behind the projection 20. The plate 22 has spaced apart rearward projections 22^a adapted to engage a fixed stud 31 to limit the swinging movement of said plate and the plate 28 also has similar projections 28^a spaced farther apart and also adapted by engagement with the stud 31 to limit the swinging movement thereof. By reason of the described frictional engagement of the plate 28 with the plate arm 22, a movement imparted to the plate 28 will move the arm 22 with it as far as permitted by the projections 22^a, such movement being sufficient to trip the shoulder 21 out from under the projection 20. For thus moving the plate 28 automatically as the playing of a record is completed, it is equipped with an outward projection 32 which extends in position to be engaged by a downwardly projecting finger 33 borne by the tone arm 34. The plate 28 also has another outward projection 35 spaced angularly from the projection 32 and equipped with a curving outer end 35^a in position to be engaged by the finger 33 as the tone arm swings outward to reset the plate 28 with reference to the arm 22; the purpose of the curving outer portion 35^a of this arm being to prevent the finger 33 from engaging behind the same in a manner so that the parts would be interlocked. The purpose of providing a range of frictional adjustment between the plate 28 and the arm 22 is so that after a record has been placed on the turn-table and before the parts are reset as presently described, the tone arm may be swung inward, so that the stylus will be located at the inner extremity of the record groove indicated at X, and such movement will result in the finger 33 engaging the projection 32 and adjusting the plate 28 with

reference to the arm 22, so that when the tone arm again reaches the same position after the parts are reset, it will be operative to trip the shoulder 21 off of the projection 20 and operate the switch and brake. The plate 19 has an inwardly projecting portion 19^b which extends inward well toward the turn-table arbor 2, and this plate portion has pivoted thereto at 36, a plate arm 37 which bears a cam projection 37^a adapted when the arm 37 is projected outward to engage one of a series of upwardly projecting pins 38 borne by the turn-table support and rotating therewith, there being as herein illustratively shown four of these pins 38 quadrantly disposed. The plate arm 37 is engaged by a tension spring 39, which tends to draw it inward so that the cam projection 37^a is out of the path of the pins 38. Said plate arm is provided with a projection 37^b extending up through a slot of the plate portion 19^b and engaging a ledge 40^a on an arm 40 which is pivoted at 41 to the plate portion 19^b and which is also engaged by the other end of the spring 39 which tends to draw said arm into position so that the ledge 40^a may engage behind the projection 37^b. The arm 37 has pivoted thereto at 42 an arm 43 which extends outward through a slot 44 in the cover plate and bears the brake 9 at its outer end. The outer portion of this arm 43 is provided with an elongated slot 45 through which passes the stud 31, so that said arm is guided in its in and out movement by the stud 31. The arm 37 is provided with an outwardly extending tail piece presenting a cam edge 46, which is adapted to engage a stud 47 as the plate 19 with the parts borne thereby are swung to re-setting position, this engagement of the cam edge 46 with the stud 47 causing the arm 37 to be swung outward so that the ledge 40^a of the arm 40 is again caught behind the projection 37^b of said arm 37. The stud 37 is adjustably fitted to be fixed support, being borne by a block clamped to the support by screws which are adjustable in slots 48.

It may now be understood that assuming the parts to be set in running position as shown in Figure 2, as the playing of a record is finished the finger 33 of the tone arm strikes the projection 32 swinging the plate 28 and with it frictionally the arm 22 to dislodge the shoulder 21 from the projection 20. This permits the arm 19 under the action of the spring 24 to swing about the pivot 13 and also to some extent about the pivot 12. This results in pulling out the movable switch member or plug 8^a de-energizing the motor. This swinging movement of the plate 19 causes the inner portion 19^b thereof to swing the arm 37 borne thereby into position so that the cam projection 37^a is engaged by the next revolving pin 38 borne by the turn-table. As this occurs

the next following pin 38 engages the outer extremity of the arm 40 as indicated in Figure 4, swinging this arm to dislodge the ledge 40^a from the projection 37^b. The 5 engagement of the first noted pin 38 with the cam projection 37^a then acts to swing the arm 37 and push outward the arm 43 causing the brake 9 borne thereby to engage the turn-table and at once stop the same.

10 As the tone arm is swung outward to permit removal of the record R and the placing of a fresh record on the turn-table, the finger 33 engaging the curving extremity 35^a of the arm 35 presses the plate 28 backward 15 with reference to the arm 22, the arm 22 being then restrained from further movement by the engagement of the inner one of the projections 22^a with the stud 31. The purpose of this setting back of the plate 28 20 with reference to the arm 22 is to insure that this plate will be so located that when the tone arm is next swung inward to the inner extremity of the groove of the record as indicated by the line X, the finger 33 will 25 engage the projection 32 to so locate the plate 28 that when the tone arm reaches the same position again after the parts have been re-set in running position as indicated in Figure 2, the finger 33 again striking the 30 projection 32 will swing the plate 28 and with it frictionally the arm 22 to dislodge the shoulder 21 from the projection 20 and permit the stop and brake mechanism to operate. When the tone arm is thus swung 35 outward, the mechanism is hence in readiness so that when a fresh record to be played is deposited on the turn-table as the hand lever 14 is swung to starting position as indicated in Figure 2, the parts are re-set, the 40 motor energized and the brake released to commence the playing of the record. To accomplish this the hand lever 14 is provided with a projection 49 which engages the plate 19 to swing the same about the pivots 45 13 and 12, so that the switch member 8^a is pressed inward, the projection 20 caught behind the shoulder 21, and the inner portion 19^b of the arm 19 swung so that the cam projection 37^a of the arm 37 is borne 50 out of the way of the pins 38. As this occurs, the cam edge 46 borne by the tail piece of arm 37 engages the stud 47 and the arm 37 is thereby swung inward against the tension of the spring 39 so as to draw the brake 9 inward out of contact with the turn-table, and the projection 37^b is caught behind the ledge 40^a, thus locking the brake in inoperative position until the parts are again tripped as described. I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having described my invention, what I claim as new and desire to secure by Letters Patent is:

1. The combination with a turn-table and tone arm, an electric motor for operating the turn-table and a brake, of mechanism for de-energizing the motor as the playing of a record is finished and for thereafter applying said brake, said mechanism embodying a trip device actuated by said tone arm and means receiving impulse from the turn-table for applying the brake.
2. Apparatus of the kind described, comprising a turn-table, a tone arm, a motor for operating the turn-table, a brake, and mechanism for de-energizing the motor and applying the brake as the playing of a record is finished, said mechanism embodying a trip device having provision for preliminary adjustment by the tone arm, and adapted for actuation thereby after the parts are re-set, and embodying also means receiving impulse from the movement of the turn-table for applying said brake.
3. Apparatus of the kind described, comprising a turn-table, a tone arm, a motor for operating the turn-table, a brake, and mechanism for de-energizing said motor and applying said brake having connections rendered operative by said tone arm at variable and selective positions thereof for different records, said mechanism embodying an adjustable trip device, manual resetting means, and embodying also connections having a cam member engageable by a projection on the turn-table for moving said brake into operative position.

In testimony whereof, I have signed my name to this specification.

JOHN C. McPHAIL.
